US00D911368S

(12) **United States Design Patent** (10) Patent No.: **US D911,368 S**
(45) Date of Patent: **** Feb. 23, 2021**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Carole Baijings**, Amsterdam (NL); **Jody Kocken**, Amsterdam (NL); **Stefan Scholten**, Amsterdam (NL); **Jae Julien**, Suwon-si (KR); **Yoo Jin Choi**, Suwon-si (KR); **Ji Hyae Kim**, Suwon-si (KR); **Hye Ryung Kim**, Suwon-si (KR); **Ji Hyun Lee**, Suwon-si (KR); **Hye Won Lee**, Suwon-si (KR)

(73) Assignee: **Samsung Electronics Co., Ltd.**, Suwon-si (KR)

(**) Term: **15 Years**

(21) Appl. No.: **29/688,267**

(22) Filed: **Apr. 19, 2019**

(30) **Foreign Application Priority Data**

Dec. 20, 2018 (KR) 30-2018-0060323

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The broken line in the FIGURE depicts the display screen or portion thereof and forms no part of the claimed design. The shading depicts a contrast in appearance.

1 Claim, 1 Drawing Sheet
